UNITED STATES PATENT OFFICE.

WILLIAM J. KERWIN, JR., OF NEW BEDFORD, MASSACHUSETTS.

AUTOMATIC OILING DEVICE FOR RUB-APRONS.

1,370,972.

Specification of Letters Patent.

Patented Mar. 8, 1921.

Application filed May 4, 1920. Serial No. 378,889.

To all whom it may concern:

Be it known that I, WILLIAM J. KERWIN, Jr., a citizen of the United States, and residing at New Bedford, Bristol county, State of Massachusetts, have invented certain new and useful Improvements in Automatic Oiling Devices for Rub-Aprons, of which the following is a specification.

This invention relates to oiling devices for leather belts or aprons such as for rub aprons on wool, shoddy or cotton waste card condensers. It embodies automatic means for constantly applying to the surface of the moving belt or apron the proper amount of oil properly distributed to keep it in good condition and soft and pliable, thus contributing to its efficiency and lasting qualities. The novel features will be apparent from the following description taken in connection with the drawings in which:

Figure 1 is a side view of my oiling device partly in section in place beneath the apron of a card condenser; and

Fig. 2 is a cross section on the line 2—2 of Fig. 1;

Since the construction and arrangement of card condensers are well known and will be understood by those skilled in the art, I have in the present drawings shown only one pair of rollers 10 and 11 carrying the apron 12, and have not considered it necessary to show the additional rollers and belts which coöperate therewith. It will be seen by reference to Fig. 2 that I place my oiling device beneath a belt between the rollers extending transversely of the movement of the belt or apron. In the form shown there are brackets 13, 14 secured to any suitable supports 15, 16, and it will be understood that these may be a part of the frame of the machine, if desired. The brackets 13, 14 carry additional brackets 17, 18, and these brackets have bottom ledges 19, 20 which support a trough 21 adapted to contain oil. The brackets 17, 18 have bearings for the ends of the parallel shafts 22, 23. The shaft 22 has an enlarged cylindrical roll 24, the upper surface of which is parallel to but slightly removed from the apron 12 which is to be oiled. The cylindrical roll 24 has on it and extending semicircularly about it a number of projecting cams 25 and it will be noted that these cams are arranged in staggered relation, separated laterally but partly overlapping longitudinally, and form practically a spiral row around the cylind-

rical roll 24. I preferably place on these cams a covering or coating 26 which will absorb and carry oil, such as leather or wool, and these oil carrying coatings or the cams themselves will come in contact with the under surface of the apron 12, although the surface of the roll 24 will not.

The shaft 23 carries a cylindrical roll 27 which is preferably larger than the roll 24 and while its upper surface is parallel with the surface of the roll 24 it is so separated that there will be no contact even with the cams carried by the roll. The cylindrical roll 27 however, has secured to its surface a projecting oil carrying member 28 which may be made of leather or wool or other material to absorb oil and which as shown extends spirally around the roll 27. This spiral oil carrying member 28 makes contact with the cams or the cam covers on the roll 24, thus transferring to those cam covers part of the oil which the member 28 carries. The shaft 23 fits in stuffing boxes 29, 30, at the ends of the oil trough 21. The shafts 22 and 23 are connected to rotate together by intermeshing gears 31, 32, but these gears should not be of the same diameter or have the same number of teeth. I prefer to make the gear 31 with twenty-eight teeth and the gear 32 with thirty teeth. The result of this is, of course, to make the two rolls 24 and 27 travel at different speeds, and also that the oil carrier 28 and the cam surfaces have a wiping action. Furthermore, those cams which do not strike the oil carrier 28 on one revolution will do so later on at some other revolution of the rolls. The rolls may be driven in any suitable way, for instance, by means of the sprocket wheel 33 which may receive its power from the same source that drives the card condenser, or from some other source. It will be observed that the oil 34 in the oil trough 21 does not extend up to the shaft 23 but that a part of the cylindrical roll 27 is submerged in it so as to make the oil carrying member 28 carry up the right amount of oil at each revolution.

It will, of course, be understood that the oiling device will be in operation as the apron of the card condenser is moving and the roll 27 through the part 28 will continuously pick up small quantities of oil and by the rubbing action oil the covers on the cams 25, thus those cams will in turn rub over the surface of the apron 12 and

transfer the oil to the apron. In practice the rolls are run at a slow rate of speed and I find that this construction properly distributes the oil and keeps the belt or apron in good shape. It will, of course, be understood that the amount of oil can be regulated somewhat by the speed and also by the amount and character of the covering on the cams.

10 Having thus described my invention what I claim as new and desire to secure by Letters Patent is:

1. In a device of the class described, the combination with a roll or cylinder having 15 on its periphery means for carrying distributed and regulated quantities of oil and adapted to make contact with a belt or apron to be oiled, of means for rotating said cylinder independently of said belt or apron 20 to bring the oil carrying means in contact with the belt or apron, and means for automatically supplying oil to said oil carrying means during the rotation of said cylinder.

2. In a device of the class described, the 25 combination with a roll or cylinder adapted to be placed under the belt to be oiled having on its outer surface at intervals projecting portions adapted to carry oil in limited 30 quantities and to make contact with the belt, a second roll or cylinder below the first carrying on a part of its surface longitudinally, means for absorbing and carrying oil making contact with the projections on the first cylinder, means for supplying oil to said 35 oil carrying means on said second cylinder, and means for rotating said cylinders at different speeds.

3. In a device for automatically oiling 40 moving belts or aprons, the combination with a cylindrical roll adapted to be placed below the belt having projections on its surface at intervals and in staggered relation adapted to make contact at the top with the under surface of the belt, a second cylindrical roll below and parallel to said first roll having on its surface a spirally arranged projection adapted to carry oil and to make contact at intervals with the projections on said first roll, a trough containing 45 oil surrounding the lower portion of said second roll and in which said roll is partially submerged, and means for slowly rotating said rolls at different speeds.

4. In a device for automatically oiling 50 moving belts or aprons, the combination with a cylindrical roll adapted to be placed

below the belt having separate staggered cam shaped projections thereon at intervals adapted to make wiping contact at the top of the roll with the under surface of the belt, a second cylindrical roll below and parallel to said first roll having projecting from its surface a spiral shaped oil carrier adapted to make contact with said cams, an oil trough having end bushings for the 55 shaft of said second roll and for partly submerging said roll in oil, and means for rotatively supporting said rolls in proper relation and for driving them at different speeds in opposite directions.

5. In a device for automatically oiling moving belts or aprons, the combination with a cylindrical roll adapted to be placed below the belt having separate staggered cam shaped projections thereon at intervals 60 covered with oil absorbing material such as leather or wool, adapted to make wiping contact at the top of the roll with the under surface of the belt, a second cylindrical roll below and parallel to said first roll having projecting from its surface a spiral shaped oil carrier composed of oil absorbing material such as leather or wool adapted to make contact with said cams, an oil trough having end bushings for the shaft 65 of said second roll and for partly submerging said roll in oil, and means for rotatively supporting said rolls in proper relation and for driving them at different speeds in opposite directions.

6. In a device for automatically oiling moving belts or aprons, the combination with end supports of two parallel cylindrical separated rolls one above the other having rotary bearings in said end supports, gear connections between said rolls for causing them to turn at different speeds, an oil trough carried by said supports below said bottom roll and in which it is partially submerged and which is provided with end bushings, oil carrying projections on said upper roll at intervals adapted to wipe over the under surface of a belt traveling above it, oil carrying means projecting from a portion of said second roll throughout its length and adapted to make contact with and leave oil on the projections on said first roll at intervals, and means for driving said rolls.

In testimony whereof I affix my signature.

WILLIAM J. KERWIN, JR.
